United States Patent Office.

ARTHUR M. ALLEN, OF NEW YORK, N. Y.

Letters Patent No. 91,060, dated June 8, 1869.

IMPROVEMENT IN VALVE-GEAR.

The Schedule referred to in these Letters Patent and making part of the same.

To all whom it may concern:

Be it known that I, ARTHUR M. ALLEN, of the city, county, and State of New York, have invented a new and improved Valve-Gear; and I do hereby declare the following to be a full, clear, and exact description thereof, which will enable those skilled in the art to make and use the same, reference being had to the accompanying drawing, forming part of this specification, in which drawing—

Figure 1 represents a side view of this invention.

Figure 2 is a plan or top view thereof, partly in section.

Figure 3 is a transverse vertical section of the same. Similar letters indicate corresponding parts.

This invention consists in the arrangement of a sliding bar, carrying a guide for a carriage, from which extends a pivot, through a slotted link, into the end of the rod imparting motion to the slide-valve of a steam-engine, said link being made to oscillate by a single eccentric on a stationary central pivot, in such a manner that the oscillating motion of the link is intercepted by the carriage, and transmitted to the valve without compelling the reversing-lever to move, and thereby a valve-gear is obtained, which is operated by a single eccentric and a single link, and which allows of reversing the engine with the greatest ease and facility.

The letter A designates a slotted link, which oscillates on a pivot, a, secured in a stationary bracket, b, said pivot being attached to a bridge, c, which extends across the slot of the link, so that it does not interfere with the motion of the pin d in the slot of the link.

This pin extends from a carriage, e, into the rod f, which transmits motion to the valve-rod g, and through it to the valve enclosed in the steam-chest B.

The carriage e is fitted on a guide, h, which extends from a slide-bar, i, in a direction transverse to the link A, and the slide-bar i connects, by a link, j, elbow-lever k, and rod l, with the reversing-lever.

The link A connects, by a rod, C, with an eccentric,

D, so that by the revolution of said eccentric, an oscillating motion is imparted to the link.

If the pin d is moved in the link A, to the position shown in fig. 1 of the drawing, right under the pivot a, the valve receives no motion; but if said pin is moved, by the action of the reversing-lever, toward either end of the link, the oscillating motion of said link is transmitted to the valve, and the engine runs in one direction, if the pin d is moved below, and in the opposite direction, if the pin d is moved above the pivot a.

But if the pin d should be connected rigidly to the end of the rod l, or any other rod or lever connected to the reversing-lever, the link would either not be able to oscillate whenever said pin should be moved toward one or toward the other end of the link, or the oscillating motion of the link would also be transmitted to the reversing-lever.

This difficulty I have overcome by connecting the pin d to a carriage, e, which is supported by the slide-bar i, said carriage being capable of moving in a direction transverse to the slot of the link.

If the pin d, in my valve-gear, is moved from under the pivot a of the link, the carriage e is caused to slide back and forth on its guide h, by the oscillating motion of the link, and the reversing-lever can remain stationary while the full motion of the link is transmitted to the valve.

Having thus described my invention, What I claim as new, and desire to secure by Letters Patent, is—

The carriage e, guide h, and slide-bar i, in combination with the pin d, sliding in the link A, and transmitting its motion to the valve, substantially as herein shown and described.

ARTHUR M. ALLEN.
